UNITED STATES PATENT OFFICE

HERBERT F. DOTSON, OF SAN ANTONIO, TEXAS

BOTTLED-BEVERAGE-VENDING MACHINE

Application filed September 8, 1927. Serial No. 218,164.

This invention relates to package vending machines, and aims to provide a mechanism for dispensing wet goods, such as a bottled beverage, whereby the drink is kept cold and 5 is dispensed by depositing a coin of predetermined value, and manipulating a plunger or like part, the operating mechanism being automatically tripped and restored to normal condition at the completion of each vending 10 operation.

The invention contemplates a sectional magazine for the bottles containing the beverage, the several sections discharging the bottles in successive order, and by gravitational action, the arrangement being such as to obviate the necessity of providing a magazine of excessive length, while at the same time assuring a positive feed of the bottles as the machine is operated.

20 The invention furthermore provides a mechanism admitting of different flavors and kinds of beverages being dispensed, since a particular operating mechanism may be selected to deliver a desired drink.

25 While the drawings illustrate a preferred embodiment of the invention, it is to be understood that in adapting the means to meet specific needs and requirements the design may be varied and changes in the minor details of construction may be resorted to within 30 the scope of the invention as claimed, without departing from the spirit thereof.

For a full understanding of the invention and the merits thereof, reference is to be had 35 to the following description and the drawings hereto attached, in which,—

Figure 1 is a front view of a bottled beverage vending machine embodying the invention.

40 Figure 2 is a vertical longitudinal sectional view thereof showing more clearly the operating means.

Figure 3 is an enlarged detail view of a portion of the operating mechanism.

45 Figure 4 is a fragmentary sectional view on the line 4—4 of Figure 3, looking to the left as indicated by the arrows.

Figure 5 is a detail view of the plunger, its guide, a portion of the coin way, the switch 50 for controlling the circuit to the motor, and

the detent for holding the plunger when moved inward.

Figure 6 is a side view of the plunger.

Figure 7 is a detail view of a sectional magazine, a portion of the obverse walls being 55 broken away.

Corresponding and like parts are referred to in the following description and designated in the several views of the drawings by like reference characters.

The operating mechanism or parts are enclosed within a suitable cabinet which may be of any appropriate design and constructed of any suitable material. It is observed that a magazine will be provided for each flavor or kind of drink to be dispensed, and that a dispensing mechanism will be associated with each of the magazines, so that any desired flavor or drink may be obtained by the patron. The operating mechanism includes an electric 70 motor and power transmitting means for each delivery mechanism, the latter being coupled to the motor by means of a peculiar mechanism brought into operation after the predetermined coin has been deposited and the operating plunger or like part thrust inward. A coin-way and plunger are provided for each delivery mechanism and, as these parts are alike, a detailed description of one will suffice for a clear understanding thereof.

75 The cabinet is designated generally by the numeral 1 and its lower portion, which contains the dispensing mechanism, is extended forwardly and provided with bins 2 for receiving the empty bottles. The numeral 3 designates a bottle cap remover and 4 a receptacle for receiving the detached bottle caps. A display case 5 is mounted upon the upper portion of the front of the cabinet, and is adapted to receive bottles containing the wet goods to be dispensed. The numeral 6 designates coin-ways which are adapted to receive a coin of predetermined value. A coin receptacle 7 is located within the lower portion of the cabinet to receive the coins as they are discharged from the coin way. An electric motor 8 is located within the cabinet and is geared to a countershaft 9 which is operated thereby. A tumbling shaft 10 is geared to the countershaft 9 and a section thereof is 100

mounted in an eccentric bearing 11 which, when rotated, moves the end section of the tumbling shaft towards and away from a friction wheel 12 which is fast to a shaft 13 to which an arm 14 is attached. A friction wheel 15 fast to the end section of the tumbling shaft 10 cooperates with the friction wheel 12, and is caused to make contact therewith or to move outward therefrom by rotating the eccentric bearing 11. The arm 14 has opposite ends projecting a like distance from the shaft 13, and is provided at opposite ends with laterally projecting pins 16 upon which are mounted sleeves 17. A curved way 18 is adapted to receive the bottles to be delivered and is formed in a side with a slot 19 through which the inner ends of the pins 16 are adapted to travel. The curved way 18 is adapted to receive the bottles at its lower end and connects with a guide 20 which receives the bottles in the delivery thereof. A gate 21 is pivoted at its lower end to the rear wall of the curved way 18 and normally extends across said way to direct the bottles outwardly therefrom to the guide 20. The gate 21 is moved rearward as the pins 16 pass thereby in the delivery of the bottles.

The bottle magazine comprises sections 22, 22^a, 22^b and 22^c, which are in communication at their lower ends. The bottoms of the sections are inclined to insure a feed of the bottles from one section to the other. A gate 23 in line with the partition separating adjacent sections is pivoted at its upper end and is free to swing at its lower end. These gates 23 are located at the lower ends of the partitions or walls separating adjacent sections. When the sections of the magazine contain bottles the gates 23 are prevented from swinging forwardly, but when the forward section is about to become exhausted the gate 23, relieved of the rearward pressure, swings forwardly and permits the bottles in the next section to move forwardly and enter the section of the magazine next in advance thereof. In this manner the sections successively discharge into the next preceding section, and by reason of the inclined bottoms of the sections, all the bottles are delivered. A chamber 24^a surrounds the upper portion of the magazine and is adapted to receive ice whereby to cool the bottles and their contents.

The plunger 24 operates through the front of the cabinet and is mounted in a guide 25 which projects through the front of the cabinet and is secured thereto. A vertical opening 26 is formed in the plunger 24 and is adapted to register with openings formed in the top and bottom of the guide 25. The lower portion of the opening 26 is constricted, as shown most clearly in Figure 6 to prevent a coin of predetermined value from passing through the opening 26 while admitting of similar articles of smaller size to pass readily therethrough. A branch tube 27 is offset at

its upper end from the plane of the plunger 24 and connects at its lower end with the coinway 6. A slot 28 is formed in the plunger 24 and intersects with the opening 26 and registers with openings formed in opposite sides of the guide 25 and is adapted to receive the forward end of a flat spring 29 which is secured at its rear end to a side of the guide 25. The forward end of the spring 29 normally extends through the opening in the adjacent side of the guide 25 and enters the slot 28 of the plunger 24. When a coin of predetermined value is received in the opening 26 it is retained therein until the plunger 24 is pushed in, thereby bringing the coin beneath the forward end of the spring 29, so that when the coin reaches a position opposite the branch 27 it is received therein by the action of the spring 29, dislodging it from the opening 26. The coin upon entering the branch 27 passes therethrough and enters the lower portion of the coinway 6, passing therefrom into the receptacle 7. When the plunger 24 reaches the limit of its rearward movement, the circuit supplying current to the motor 8 is closed, and at the same time the plunger is made secure by means of a detent or latch 28 engaging a stop 29 on the plunger. The detent or latch 28 is pivoted at its rear end and extends forwardly. A stop 30 holds the latch 28 in normal position. A rod 31 connects the latch 28 with an extension of the eccentric bearing 11 and when the forward end of the latch 28 is elevated the eccentric bearing 11 is turned, thereby moving the end section of the tumbling shaft 10 to bring the friction wheel 15 in contact with the friction wheel 12, whereby the shaft 13 is rotated to effect a corresponding rotation of the arm 14 which, as stated, is fast thereto. A circuit closer 32, carried by the plunger 24, is adapted to be pressed between two contacts 33 which are thereby electrically connected to close the circuit. The elements 32 and 33 constitute parts of a circuit closing switch. A spring 34 is connected at one end to the plunger and at its opposite end to the guide 25, and when the plunger is moved inward, the spring 34 is stretched and when the plunger is released from the latch 28 the spring 34 returns it to normal position. The forward end of the latch 28 is curved upwardly and forwardly, and when the plunger 24 is moved rearwardly the stop 29 rides on the curved end of the latch and elevates the same, thereby moving the rod 31 and turning the eccentric bearing 11.

The latch 28 is adapted to be released by an arm 35 which is pivoted at its forward end and which is adapted to have its rear end engaged under the latch 28 to lift the same and disengage it from the stop 29. An arm 36 is connected with the pivotal end of the arm 35 and projects into the path of the sleeve 17 at the end of the ejector or deliverer 14. The arm 36 is located above the upper end of the

way 18, hence the sleeve 17 engages the arm 36 and moves it and the arm 35 in the final movement of the ejector or deliverer, thereby releasing the plunger which is returned to normal position by means of the spring 34, with the result that the circuit supplying current to the motor 8 is broken and the delivery mechanism thrown out of action by movement of the wheel 15 away from the wheel 12. To operate the machine a coin of predetermined value, such as a nickel, is dropped into a selected coinway, depending upon the beverage to be obtained. The coin is received in the opening 26 of the plunger 24, and effects release of the plunger by disengaging a catch 37 therefrom, as indicated most clearly in Figure 5 of the drawings. The plunger, being released, is pressed inward and closes the circuit to the motor, while at the same time the latch 28 engages the stop 29 and holds the plunger in rearward position against the tension of the spring 34. As the plunger 24 reaches the limit of its inward movement, the spring 29 dislodges the coin from the opening 26, said coin being received in the branch 27 and directed to the receptacle 7 by means of the lower portion of the coinway 6. Upward movement of the latch 28 effects rotation of the eccentric bearing 11 and throws the friction wheel 15 into engagement with the friction wheel 12, thereby coupling the motor to the dispensing mechanism. Rotation of the shaft 13 effects a corresponding movement of the ejector or deliverer 14, whereby the pin 16 at the lower rear end of the arm 14 is caused to sweep through the way 18 and deliver a bottle in position to be removed, as indicated most clearly in Figure 2 of the drawings. As soon as the pin 16, traveling through the way 18, clears the same it operates the arm 36 and the arm 35 connected therewith. This elevates the latch 28 and disengages it from the plunger which is returned to normal position by means of the spring 34, thereby breaking the circuit to the motor and effecting movement of the bearing 11, whereby the motor is disconnected from the delivery mechanism, whereby the parts are restored to normal position, to be again actuated upon the deposition of a coin in one of the coin-ways.

Having thus described the invention, I claim:

1. In a vending machine, a curved way slotted in its outer side, and an ejector pivoted concentric with the way and having a laterally extending element adapted to pass through the slotted side of the curved way to engage an article deposited in the way and travel from end to end of the way for delivering the engaged article therefrom.
2. In a vending machine, a curved way adapted to receive articles to be dispensed, and an arm pivoted intermediate its ends concentric with the way and provided at oppo-

site ends with delivery elements adapted to sweep through the curved way and engage and deliver the articles supplied to the way.

3. In a vending machine, the combination of a motor, a delivery mechanism, coupling means between the motor and delivery mechanism, an operating member, a latch for holding the operating member when moved inward, and means connecting the latch with said coupling means for shifting the latter to operative position and permitting the motor to operate the delivery mechanism.

4. In a vending machine, the combination of a motor, a plunger, a delivery mechanism, means coupling the motor to the delivery mechanism and including a movable bearing, a latch adapted to engage the plunger and hold it when pressed inward, and connecting means between the latch and movable bearing whereby to effect coupling between the motor and delivery mechanism when the plunger is pressed inward.

5. In a vending machine, the combination of an electric motor, a circuit closing switch, a plunger adapted when operated to close the said switch, a latch adapted to engage the plunger and hold it when pressed in, delivery mechanism, coupling means for connecting the motor to the delivery mechanism, connecting means between the said latch and coupling means, and a trip mechanism adapted to be operated by means of the delivery mechanism to effect release of the plunger to admit of the parts returning to normal position.

In testimony whereof I affix my signature.
